UNITED STATES PATENT OFFICE.

JAMES H. WILSON, OF CHICAGO, ILLINOIS, ASSIGNOR TO WILSON & BENNETT MFG. CO., OF CHICAGO, ILLINOIS.

DESIGN FOR A PAIL.

58,053.

Specification for Design.

Patented May 31, 1921.

Application filed November 8, 1919. Serial No. 336,748. Term of patent 14 years.

To all whom it may concern:

Be it known that I, JAMES H. WILSON, a citizen of the United States, residing at Chicago, in the county of Cook and State of Illinois, have invented a new, original, and ornamental Design for Pails, of which the following is a specification, reference being had to the accompanying drawing, forming part thereof.

The figure shown in this drawing is a perspective view of a pail showing my new design.

I claim:

The ornamental design for a pail as shown.

JAMES H. WILSON.
